UNITED STATES PATENT OFFICE.

JOHANN TRAUGOTT HOHBERGER, OF CHICAGO, ILLINOIS, ASSIGNOR, BY DIRECT AND
MESNE ASSIGNMENTS, TO ARTHUR R. MORSE, OF CHICAGO, ILLINOIS.

CANDY-CUTTING MACHINE.

1,031,647.

Specification of Letters Patent. Patented July 2, 1912.

Application filed February 19, 1909. Serial No. 478,962.

To all whom it may concern:

Be it known that I, JOHANN TRAUGOTT HOHBERGER, a subject of the Emperor of Germany, residing at Chicago, county of Cook, and State of Illinois, have invented 5 certain new and useful Improvements in Candy-Cutting Machines, of which the following is a description.

My invention relates to means for dividing, cutting, or otherwise suitably forming 10 into pieces of suitable length a strip of candy or like material preferably while the same is in a plastic or semi-plastic condition.

The object of my invention is to provide 15 a simple, durable, and efficient device of the kind described wherein the relative movements of the coöperating cutting blades as they approach each other during the cutting operation are arranged to suit the requirements of the particular material upon which 20 the device is adapted to operate.

To this end my invention consists in the novel construction, arrangement, and combination of parts herein shown and described, and more particularly pointed out 25 in the claims.

In the accompanying drawings, wherein like or similar reference characters indicate like or corresponding parts; Figure 1 is a 30 side elevation of my device. Fig. 2 is a top plan view of the same with parts removed and broken away to more clearly show the construction. Fig. 3 is a perspective view of the cover, or outer cam plate for assisting in controlling the movement of the cutting blades. Fig. 4 is a perspective detail of the stationary inner cam for assisting in controlling the movement of the blades. Figs. 5 and 6 are details of the inner cam 35 support and its associated parts. Fig. 7 is a detail of a portion of one of the blade carrying members. Fig. 8 is a perspective detail of a blade. Fig. 9 is an enlarged section taken substantially on line 9—9 of Fig. 1; and Fig. 10 is an enlarged section 40 through the cutting heads taken substantially on line 10—10 of Fig. 2.

In the preferred form shown in the drawings, my device consists of a pair of rotatable shafts 1 and 2, each mounted in suitable

bearings upon the frame of the machine. Cutter heads or members 4 and 5 are mounted upon the extremities of the shafts 1 and 2 respectively and are each rigidly secured thereto, the relative position of the parts being such that the periphery of the members 4 and 5 will be brought into suitable relation with each other so that the cutting blades 6—6 positioned upon each head will be brought into suitable relation with each other to substantially sever the material passing between them. The heads 4 and 5 may be of any suitable construction and are preferably substantially similar. As shown each of the heads is provided with a peripheral wall 7 having a concentric flange 8 projecting at each side, a web or plate 9 having a central hub 10 is formed integral with or rigidly secured to the wall 7 for securing the head in position upon the shaft, and an inwardly projecting flange 11 is provided at the opposite edge of the wall 7 thereby providing a chamber 12 within each head between the plate 9 and flange 11 extending to the wall 7. Any desired number of substantially radial or otherwise suitably arranged slots 14 are provided in the periphery of each head extending inward beyond the wall 7 and terminating at a substantially uniform distance from the center of the member. The blades 6—6 which are preferably of substantially uniform width are positioned in these slots and adapted to move substantially radially of the member.

Any suitable means may be provided for controlling the position and movements of the blades 6 in the heads 4 and 5. As shown a pair of plates 15 and 16 are secured to the outer face of each member to close the ends of the slots 14 and control the transverse position of the blades 6 in their respective slots.

The radial position of the blades may be controlled in any desired manner, as shown a pair of stationary cams or guides are provided adapted to engage the blades between them. In this form a cam 17 or equivalent means is rigidly positioned in each chamber 12 so that as the head revolves the inner edge of the blades 6 will successively engage

95

100

the face of the cam to force them outward. A cover plate or cam 18 is arranged to partially inclose the members 4 and 5, suitably formed to engage the outer edges of the blades 6 to control the outward movement thereof. In the form shown, the cam 18 is formed to hold the blades snugly at the inner limit of their movement in their respective grooves 14 until they arrive at a point where 5 the blades engage the cam 17; at this point the cam 18 is formed to correspond with the form of the cam 17 so that at this point the cams coöperate first to move the blades outward and then to return each blade to its 10 normal position, the movement corresponding to the peculiar form of the cams. Obviously these cams may be formed to provide for any desired movement of the blades at any point in the rotation of each head 15 depending upon the particular material upon which it is intended that the machine is to operate. In the form shown, these blades are arranged to move outward to substantially the limit of their movement, 20 after which they are permitted to return to their normal position in the member the return movement being so adjusted that the coöperating blades will approach each other with a substantially uniform movement. 25

Any suitable means may be provided for directing the material to be operated upon into the space between the members 4 and 5. In the form shown, a suitable opening 19 is 30 provided in the plate 18 and an inclined curved lip 20 arranged to direct the material to, and support and control the same until it is engaged by, the blades 6, a suitable opening 21 is also provided at the opposite side of the plate 18 to permit the discharge 35 of the material from the space between the members. A guide or chute 22 is provided to direct the discharged material onto a conveyor or other suitable means for disposing of the same. 40

Any suitable means may be provided for supporting the various parts in position. In the form shown, two brackets 24 and 24 are provided each rigidly secured to a base or foundation plate 26. The shaft 1 is supported in suitable bearings formed integral with or rigidly secured to the respective brackets. The shaft 2 may be similarly mounted, but in the preferred construction shown, a suitable opening 29 is provided in 45 each of the brackets with the top and bottom wall of each opening substantially horizontal. A bearing 30 of suitable height to snugly fit within the opening 29 and arranged to move horizontally therein to permit 50 mit of side adjustment is provided. Suitable means are provided for controlling the position of the bearing 30 in the opening 29. In the bracket 24 adjusting screws 31 and 32 are provided at opposite ends of the

opening adapted to engage the bearings between them and accurately control its position in the opening. In the bracket 25 however, as the pressure due to the operation of the machine always tends to separate the members 4 and 5, a suitable pocket is provided at the end of the opening 29 adjacent the bearing 28 and a spring 33 is positioned with one end in the pocket and its opposite end projecting into the opening 29 adapted to engage the bearing to resiliently force the 65 same toward the opposite end of the opening. An adjusting screw 34 is provided in the opposite end of the opening to engage the bearing and accurately limit its movement in that direction. 70

The members 4 and 5 may be secured to the shafts 1 and 2 in any suitable manner. In the form shown, a fixed key or projection 35 is provided upon the shaft 1 and a corresponding slot is formed in the hub 10 85 of the member 4 to coöperate with the projection 35 to prevent rotation between the shaft and member. A set-screw 36 is also provided in the hub, arranged to engage the projection 35 or other suitable portion 90 of the shaft and prevent longitudinal movement between the head and shaft. 80

The member 5 may be attached to the shaft 2 in the manner above described, but it is obvious that in a device of this character it is desirable that the cutting edge of the coöperating blades 6 should accurately meet to secure the most satisfactory operation. For this reason means are preferably provided for adjusting the rotary position 95 of one of the heads upon its shaft. In the other form shown, suitable slots 37—37 are provided in that portion of the shaft 2 projecting beyond the bearing 30 and a pair of set-screws 38 and 39 are provided in the 100 hub 10 of the member 5 each arranged to enter one of the slots and engage the part 40 of the shaft so that by loosening one set-screw and tightening the other the member 5 may be slightly rotated upon the shaft so 110 as to adjust the relation of the blade 6 in the head 5 with those upon the head 4. 105

The cover plate or cam 18 may be supported in any desired manner. In the form shown a plurality of arms 45 are rigidly secured at one end to the plate 18 and at their opposite ends to the bracket 25. The space in the cover plate 18 for the head 5 is preferably of suitable form to permit sufficient lateral adjustment of the head to suit the 115 different kinds or conditions of material to be operated upon. 120

The cams 17 may be rigidly supported in position within the heads 4 and 5 in any desired manner. In the form shown, each 125 cam is provided with a stem 46 positioned slightly to one side of its center line with the side of the stem adjacent the center line

slightly wider than the opposite side and adapted to be engaged by a stationary member extending into the chamber 12 for this purpose. Any suitable means may be provided for engaging the stem 46 to support the cams 17 in position. As shown a cylindrical tubular member 47 is provided having a jaw or face 48 at one end formed to co-operate with the stem 46 (see Figs. 5 and 6). 5 A rod 49 is also provided formed to snugly fit the interior of the part 47 and provided with a head 50 preferably of substantially the same diameter as the part 47 and having a jaw or face 51 adapted to co-operate 10 with the jaw 48 to form a substantially dove-tail clamp of suitable size and form to engage the shank 46.

The relative position of the parts 47 and 49 to produce the desired clamping action 20 may be controlled in any suitable manner. In the form shown, the rod 49 is of sufficient length to extend entirely through the member 47 and its extremity is threaded and provided with a suitable nut 56 adapted to 25 bear against the end of the part 47 to draw the head 50 firmly toward the part 47 to firmly clamp the stem 46 between them.

Any suitable means may be provided to support the parts 47 and 49 in position. In 30 the form shown, a stand 52 is provided upon the base plate 26 with suitable bearings 53—53 formed therein each adapted to receive the part 47. A set-screw 54 or other suitable means is provided in the wall of 35 each of the bearings 53 adapted to engage the part 47 to rigidly hold the same in position in the bearing.

The free end of each of the cam supports 40 may be held against transverse movement in any desired manner to insure the satisfactory operation of this portion of the device. In the form shown the central bore of each head extends entirely through the hub 10 and plate 9, but the shaft upon which each 45 head or member 4 and 5 is mounted does not extend to the inner face of the plate 9 thereby leaving a slight central recess in the plate 9 adapted to engage a portion of the head 50, which is formed to fit the recess, thereby 50 rigidly supporting the cam in position. As shown a projection 55 is provided upon the central portion of the plate 9 within the chamber 12 to increase the depth of the recess above described.

55 Any suitable means may be provided for rotating the shafts 1 and 2. In the form shown, a pair of gears 57—57 are mounted upon and rigidly secured to the shafts 1 and 2 respectively and a drive shaft 58 is rotatably mounted in suitable bearings upon 60 the brackets 24 and 25 with a pinion 59 rigidly secured thereto and arranged to mesh with one of the gears 57. Any suitable means may be provided for rotating the

shaft 58. As shown a belt-pulley 60 is rigidly secured to the shaft so that my device may be connected by a belt or other suitable transmitting means to any suitable source of power (not shown) for operating the same. If desired a similar pulley 61 70 may be loosely mounted upon the shaft 58 so that when it is desired to stop the machine the driving belt may be shifted to this "loose" pulley. A belt shifter 62 of the usual form is shown in suitable brackets 75 upon the plate 26 for directing the belt from one pulley to the other.

The material after passing between the heads 4 and 5 as hereinbefore described is received upon a carrier or belt 23 which 80 moves it to any desired point and discharges the separate pieces into a suitable receptacle. The conveyer may be of any desired form or construction. In the form shown the belt 23 is arranged upon a pair of pulleys 85 63 and 64 suitably arranged to hold the belt at the proper tension. The pulley 63 is secured to a shaft 65 rotatably mounted in suitable bearings upon the brackets 24 and 25. A gear or pinion 66 is also secured 90 to the shaft 65 and arranged to mesh with the pinion 59 to drive the conveyer. The pulley 64 is secured to a shaft 67 rotatably mounted in suitable bearings upon a stand 68 at the opposite or discharge end of the 95 conveyer. The upper portion of the belt 23 extends through a box, trough, or other suitable means 69 with walls or parts provided on each side of the belt adapted to hold the material upon the belt until it reaches the 100 end of the conveyer and is discharged.

In the preferred construction shown the heads 4 and 5 are so adjusted that the material passing between them is not entirely severed, and the conveyer 23 is of sufficient 105 length to permit the material to harden sufficiently, so that when it arrives at the end of the conveyer the material will break apart as it leaves the conveyer. Any suitable means may be provided to insure the cooling 110 or hardening of the material upon the conveyer. In the form shown an air pipe 70 is provided attached to a blower or other convenient source of compressed air, (not shown) and extends preferably substantially parallel to and slightly above the box or trough 69. A plurality of openings or nozzles 71 are provided in the bottom of the pipe 70 by which the air from the tube is directed upon the material in the trough. 115 The end 72 of the pipe 70 is preferably only slightly contracted or left entirely open, and so positioned as to direct a blast of air into the receptacle arranged for receiving the severed material from my machine to 120 prevent the warmth of the interior of the material from tending to soften its exterior. 125

As shown a slide 73 is provided upon the

stand 68 and a suitable beater 74 is provided having a plurality of arms 75 adapted to successively strike the material passing over the pulley 64 to insure the detachment of 5 the severed pieces. Each of the arms 75 is preferably provided with a brush or wiper 76 at its outer end for engaging the material so as to avoid breaking or marring the same.

Any suitable means may be provided for 10 rotating the beater 74. In the form shown, the shaft 67 is extended beyond the bracket 68 and provided with a gear 77 adapted to mesh with a pinion 78 rigidly secured to a shaft 79 rotatably mounted upon the stand 15 68 and to which the beater 74 is also secured.

Having thus described my improvement, it is obvious that various immaterial modifications may be made in my device without departing from the spirit of my invention, 20 hence I do not wish to be understood as limiting myself to the exact form and construction shown.

What I claim as new, and desire to secure by Letters Patent is:—

25 1. In a device of the kind described, a frame, a rotatable member mounted upon said frame, a plurality of blades positioned upon said member each adapted to move substantially radially thereof, and a part 30 extending transversely of the blades and jointly supported upon said frame and said member for successively controlling the position of said blades.

35 2. In a device of the kind described, a frame, a rotatable member mounted upon said frame and provided with a central chamber, a plurality of blades positioned upon said member, each adapted to move substantially radially thereof and a part 40 extending transversely of the blades and jointly supported upon said frame and said member for successively controlling the position of said blades.

45 3. In a device of the kind described, a frame, a rotatable member mounted upon said frame and provided with a central chamber, a plurality of blades positioned upon said member each adapted to move substantially radially thereof with a part 50 extending into said chamber, a part extending transversely of the blades and jointly supported upon said frame and member for successively controlling the position of said blades.

55 4. In a device of the kind described, a frame, a rotatable member mounted upon said frame, a plurality of blades positioned upon said member each adapted to move substantially radially thereof, a stationary 60 part extending transversely of the blades and jointly supported upon said frame and said member for successively controlling the position of said blades.

5. In a device of the kind described, a

frame, a rotatable member mounted upon 65 said frame and provided with a central chamber, a plurality of blades positioned upon said member each adapted to move substantially radially thereof, and a stationary part extending transversely of the 70 blades and jointly supported upon said frame and said member for successively controlling the position of said blades.

6. In a device of the kind described, a frame, a rotatable member mounted upon 75 said frame, a plurality of blades positioned upon said member each adapted to move substantially radially thereof, a part extending transversely of the blades and jointly supported upon said frame and said 80 member adapted to coöperate with mechanism partially inclosing said member for successively controlling the position of said blades.

7. In a device of the kind described, a 85 pair of rotatable members and a plurality of radial blades adjustably mounted upon each member, in combination with means for automatically adjusting the position of said blades, comprising means partially inclosing 90 said members and engaging said blades provided with a chute extending therethrough for directing material into the space between said members.

8. In a device of the kind described, a 95 pair of rotatable members each provided with a chamber upon its interior, a plurality of movable rectangular blades positioned upon each member, and means for rotating said members to successively bring the 100 blades upon one member into coöperative relation with the blades upon the other member, means positioned in said chamber extending across the inner face of the blades adapted to successively engage said blades 105 to temporarily control their radial position.

9. In a device of the kind described, a pair of rotatable members each provided with a chamber upon its interior a plurality of blades positioned upon each member, and 110 means for rotating said members to successively bring the blades upon one member into coöperative relation with the blades upon the other member, and a cam positioned within each chamber adapted to co-operate with a cam partially inclosing 115 said members adapted to engage said blades between them to control their radial position.

10. In a device of the kind described, a pair of rotatable members each provided 120 with a chamber upon its interior, a plurality of blades positioned upon each member, and means for rotating said members to successively bring the blades upon one member into coöperative relation with the blades 125 upon the other member, and a stationary cam positioned within each member adapted to coöperate with a stationary cam partially

inclosing said members and adapted to engage said blades between them to control the radial position of the blades.

11. In a device of the kind described, a frame, a rotatable member mounted upon said frame and provided with a central chamber, a plurality of blades positioned upon said member each adapted to move substantially radially thereof, a stationary part extending transversely of the blades and jointly supported upon said frame and said member adapted to coöperate with mechanism partially inclosing said member for successively controlling the position of said blades.

12. In a device of the kind described, a frame, a rotatable member mounted upon said frame and provided with a central chamber, a plurality of blades positioned upon said member each adapted to move substantially radially thereof, a stationary cam positioned within said chamber with its face extending transversely of the blades and jointly supported upon said frame and said member for successively controlling the position of said blades.

13. In a device of the kind described, a pair of rotatable members each provided with a chamber upon its interior, a plurality of movable rectangular blades positioned upon each member with a part of each blade extending into said chamber, means for rotating said members to successively bring the blades upon one member into coöperative relation with the blades upon the other member, means positioned in said chamber extending across the inner face of said blades adapted to successively engage said blades and coöperate with means at the periphery of said members to control the radial position of said blades.

14. In a device of the kind described, a pair of rotatable members each provided with a chamber upon its interior, a plurality of radial blades upon each member, with a part of each blade extending into said chamber, means for rotating said member to successively bring the blades upon one member into coöperative relation with the blades upon the other member, and a cam positioned within said member adapted to coöperate with a cam partially inclosing said members adapted to engage said blades between them to control their radial position.

15. In a device of the kind described, a pair of rotatable members, each provided with a chamber upon its interior, a plurality of radial movable blades positioned upon each member, with a part of each blade extending into said chamber, means for rotating said members to successively bring the blades upon one member into coöperative relation with the blades upon the other

member, and a stationary cam positioned within said chamber adapted to coöperate with a stationary cam partially inclosing said members adapted to engage said blades between them to control their radial position.

16. In a device of the kind described, a pair of rotatable members, each provided with a chamber upon its interior, a plurality of radial movable blades positioned upon each member with a part extending into said chamber, means for rotating said members to successively bring the blades upon one member into coöperative relation with the blades upon the other member, and a cam positioned within said chamber adapted to coöperate with a cam partially inclosing said members adapted to engage said blades between them to control their radial position.

17. In a device of the kind described, a pair of rotatable members, each provided with a chamber upon its interior, a plurality of movable blades positioned upon each member with a part of each blade extending into said chamber means for rotating said members to successively bring the blades upon one member into coöperative relation with the blades upon the other member, and adjustable means extending into each of said chambers extending across the inner face of said blades with a part engaging said members adapted to successively engage said blades to partially control their radial position.

18. In a device of the kind described, a pair of rotatable members, each provided with a chamber upon its interior, a plurality of movable blades positioned upon each member with a part of each blade extending into said chamber means for rotating said members to bring the blades upon one member into coöperative relation with the blades upon the other member, a cam positioned within said chamber adapted to successively engage said blades to partially control their radial position, and means rigidly supported at one end extending into said chamber and engaging said member adapted to rigidly support said cam in position.

19. In a device of the kind described, a frame, a rotatable member mounted upon said frame and provided with a central chamber, a plurality of blades positioned upon said member each adapted to move substantially radially thereof, a stationary cam positioned within said chamber with a part extending transversely of said blades and jointly supported upon said frame and said member said cam being adapted to coöperate with mechanism partially inclosing said member for successively controlling the position of said blades.

20. In a device of the kind described, a rotatable member provided with a chamber upon its interior, a plurality of blades positioned upon said member with a part of each blade extending into said chamber, and means positioned within said chamber adapted to engage said blades to move the same outward, and a pair of cams partially inclosing said member and engaging the

ends of said blades to control their position.

In testimony whereof, I have hereunto signed my name in the presence of two subscribing witnesses.

JOHANN TRAUGOTT HOHBERGER.
